UNITED STATES PATENT OFFICE.

WILLIAM J. BURTON, OF CHICAGO, ILLINOIS.

MACHINE FOR MAKING SWITCHBOARD-CORDS.

No. 830,295.

Specification of Letters Patent.

Patented Sept. 4, 1906.

Application filed September 5, 1905. Serial No. 276,981.

To all whom it may concern:

Be it known that I, WILLIAM J. BURTON, a citizen of the United States, residing at Chicago, county of Cook, State of Illinois, have 5 invented a certain new and useful Improvement in Machines for Making Switchboard-Cords; and I declare the following to be a full, clear, and exact description of the invention, such as will enable others skilled in 10 the art to which it pertains to make and use the same, reference being had to the accompanying drawings, which form a part of this specification.

My invention relates in general to apparatus for coiling wire, and more particularly 15 to a machine for making switchboard-cords.

In United States Letters Patent No. 789,651, covering a joint invention of C. L. Burlingham and myself, and in United States 20 Letters Patent No. 789,652, covering a sole invention of mine, are covered switchboard-cords comprising one or more electrical conductors wound in a continuous spiral, the 25 conductors being composed of a tenacious wire surrounded by a good conducting material. The manufacture of this type of switchboard-cords manually is a slow and expensive operation and results in cords the 30 various convolutions of which are not always uniform.

The primary object of my invention is to provide a machine for making switchboard-cords of the type covered by the patents referred to, by means of which cords composed 35 of one or more conductors may be automatically manufactured, thereby reducing the expense and resulting in more perfect cords being formed.

A further object of my invention is to provide a machine for winding into parallel convolutions wire, which will be comparatively simple in construction and efficient in operation.

My invention, generally described, 45 consists in a rotary carrier, means for rotatably supporting one or more spools of wire upon said carrier, a mandrel with respect to which the carrier rotates and around which the wire is coiled, means for drawing the coiled 50 wire from the mandrel, and means for relatively rotating the carrier and mandrel.

My invention will be more fully described hereinafter with reference to the accompanying drawings, in which the same is illustrated

as embodied in a convenient and practical 55 form, and in which—

Figure 1 is a plan view; Fig. 2, a vertical sectional view on line 2 2, Fig. 1; Fig. 3, an enlarged sectional view on line 3 3, Fig. 2; Fig. 4, an enlarged detailed view of the mandrel; Fig. 5, a sectional detailed view of one of the adjustable guides; Fig. 6, a plan view of the mandrel and guides around the same; Fig. 7, an elevational view of the power connections, and Fig. 8 a detailed sectional view 65 of the clutch.

The same reference characters are used to designate the same parts in the several figures of the drawings.

Reference-letter A indicates a table or 70 other suitable support, preferably mounted upon legs a a.

B designates a supporting-frame mounted above the table A and supported thereon by 75 interposed posts b b.

Secured to the table A and projecting upwardly therefrom is a tube D, the lower end of which is screw-threaded and projects below the table. Any suitable means may be provided for rigidly uniting the tube to the 80 table—such, for instance, as a lock-nut d between which and the under side of the table a washer may be interposed. Concentrically located within the tube D is a post D', the upper end of which is provided with a flange 85 overlying the upper end of the tube, while its lower end is screw-threaded and projects below the tube.

d' indicates a lock-nut engaging the lower end of the post and rigidly securing the post 90 within the tube.

Rotatably surrounding the tube D is a gear-wheel G, having a hub g, upon which rests a carrier H, the carrier being rigidly secured to the hub in any suitable manner—as, 95 for instance, by one or more dowel-pins h. Secured to the upper surface of the carrier H are a plurality of tubular supports K, four being shown for convenience. One or more spools or reels L, containing wire, are rotatably mounted upon the supports K and are retained thereon by bolts k extending through the spools into engagement with the supports K.

Mounted upon the upper end of the post 105 D' is a rod E, carrying at its upper end a mandrel F. The lower end of the rod E engages a screw-threaded opening in the upper

end of the post D' and is retained in such engagement by a lock-nut e'. The mandrel F is provided with an enlarged lower end f, seated within a recess in the upper end of the rod E. A cap E', having a conical exterior surface, surrounds the reduced screw-threaded upper end of the rod E and retains the mandrel tightly secured thereto.

Secured to the carrier H, around the center thereof, are a plurality of brackets O, the number of such brackets corresponding to the number of supports K. Each of the brackets O adjustably supports a guide P, the upper ends of such guides having holes therethrough.

15 The lower end of each guide P is slotted vertically to receive the head of a bolt p, such bolt extending through the respective supporting-bracket O and serving to clamp the guide thereto by means of the nut p'.

20 Located adjacent each of the supports K is a bracket M, to which is secured a leaf-spring m, the free end of which is adapted to engage the periphery of the lower end of the spool L, mounted upon the adjacent support. In order to regulate the pressure with which each spring m engages the corresponding spool, a screw-threaded bolt m' is provided, which passes through a post M' and bears against the spring m. A lock-nut m² is 25 preferably provided to secure each bolt m' in its adjusted position, so as to maintain a given pressure between the spring m and the spool engaged thereby.

Projecting upwardly from the carrier H 35 adjacent each spool is a bracket N, within the upper end of which is mounted a pin n, having a hole through the upper end thereof. Also supported upon each bracket N adjacent the pin n is a rod N', having grooves around 40 its outer surface.

The carrier H may be rotated by any suitable power connections, for convenience there being shown a belt-pulley R and interposed gearing. The belt-pulley is journaled 45 within the bracket A', secured to and projecting laterally from the table A, such bracket having a depending arm a', in which is rotatably supported a bearing of the pulley R. Fixed to the pulley R is a beveled gear r, meshing with a beveled gear S, loosely mounted upon a vertical shaft S⁴. The vertical shaft is journaled at its lower end in a bearing a², carried by a bracket A², depending from the table A. The shaft S⁴ extends 50 through a bearing b², carried by the extension B² of the support B. Any suitable means may be provided for clutching the beveled gear S to the shaft S⁴. In the drawings I have shown clutch means comprising 55 a hand-lever S', fulcrumed at one end s' in the bracket A² and loosely surrounding, intermediate of its ends, the shaft S⁴. Surrounding the shaft above the lever S' is a collar S², having upwardly-projecting clutch-fingers s², adapted to engage lugs s on the

beveled gear S. A block S³ is fixed to the shaft S⁴ and projects radially between the clutch-fingers s² thereon, thereby rotatably connecting such fingers with the shaft S⁴. The lever S' has pivotally connected thereto a latch S⁵, the upper end of which extends through a guide a⁵, fixed to the table A. The upper end of the latch S⁵ is provided with a hook adapted to engage the upper end of the guide a⁵, such engagement being effected by a spring s⁵, secured at its lower end to the latch and engaging the interior of the guide, as clearly shown in Figs. 1 and 2.

Fixed upon the shaft S⁴ is a worm t, meshing with a worm-wheel T, the journals of which are mounted in bearings carried by a bracket t', projecting from one of the posts b. Rigidly secured to the stub-shaft T', on which the worm-wheel T is fixed, is a gear-wheel T², which meshes with a gear-wheel t², fixed upon the end of a horizontal shaft U. The horizontal shaft is journaled in a bearing b³ on the extension B² of the support B and also in a bearing b' on a support B', projecting from the support B. A gear-wheel U' is fixed 90 upon the shaft U and meshes with a gear-wheel U², fixed upon a short shaft u². The shaft u² is journaled at its ends in bearings carried by brackets C' and C², mounted upon the support B. The ends of the shaft u² engage elongated slots in the brackets C' C² and are adjustably retained therein in the manner shown in Fig. 3. A follower u³ engages each end of the shaft u² and is forced against the same by a spring U³, the tension of which is 100 regulated by a bolt U⁴, extending through a plate u⁴, carried at the outer end of the corresponding bracket C' or C².

Fixed to the meshed gear-wheels U' U² are pulleys V' and V², having concave peripheries. Carried by the brackets C' C² is a bracket W, having an extension w, carrying a leaf-spring W'. An adjustable bolt w' extends through the extension w and engages the upper surface of the spring W'. 110

The operation of my invention is as follows: One or more spools L, containing a conductor, are mounted upon the supports K on the carrier H. The conductor l, which consists of a tenacious interior wire surrounded by copper wire, has been made in any suitable manner and wound upon the spools L prior to inserting such spools in the machine herein described. The number of spools mounted upon the carrier may be 115 varied according to whether the cord is to comprise one or more conductors. The conductor from each spool is threaded through the hole in the pin n adjacent the same and then turned one or more times around the 120 adjacent grooved rod N', thence passes through the hole in the upper end of the adjacent guide P. The conductors leading from the several spools when more than one spool is used are similarly guided to the mandrel 125 130

F, after which the machine is put in operation. In order to rotate the table, the hand-lever S' is drawn upwardly, so that the catch S⁵ engages the upper end of the guide a⁵ and 5 retains the clutch-fingers s² in engagement with the lugs s on the beveled gear S, thereby locking such gear to the shaft S⁴. The power-belt having been applied to the pulley R, the rotary motion imparted thereto is communicated 10 by the beveled gear r to the beveled gear S, which rotates the shaft S⁴. The rotation of the shaft S⁴ is transmitted, through the gear-wheel G' fixed thereon and the gear-wheel G, driven thereby, through the 15 idler-gear G², to the carrier H. The carrier H is consequently rotated around the mandrel F and the conductor from each spool wound around the mandrel, thereby forming the conductor into a coil comprising parallel 20 convolutions. The coiled wire extending above the mandrel passes between the grooved pulleys V' and V², which are rotated in opposite directions, upwardly from the mandrel, so that the cord as it is formed is 25 drawn away from the mandrel. The rotary motion is imparted to the guide-pulleys V' V² from the shaft S⁴ through the medium of the worm t, worm-wheel T, stub-shaft T', gear-wheel T², and gear-wheel t², fixed upon the 30 shaft U, which shaft carries the gear-wheel U'. When it is desired to discontinue the operation of the machine, the latch S⁵ is disengaged from the guide a⁵, which permits the lever S' to drop and remove the clutch-fingers 35 s² from engagement with the lugs on the beveled gear S, permitting the beveled gear to idly rotate upon the shaft S⁴. When desired, the machine may be operated manually by rotating the shaft S⁴ by means of the 40 crank s⁴.

The machine is capable of various adjustments in order to render the same capable of use in making switchboard-cords comprising one or more conductors. The number of 45 spools mounted upon the carrier corresponds to the number of conductors of which the cord is to be composed. When more than one spool is mounted upon the carrier, the guides P are so adjusted that the conductors 50 leading from the several spools will be directed to the mandrel at different heights, thereby insuring the even winding of the plurality of conductors around the mandrel. The rotation of the spools upon the carrier is 55 regulated by means of the springs m engaging the peripheries of the spools, the tension of which may be regulated by means of the screw-threaded rods m'. The tension of the conductor as it passes from its spool to the 60 mandrel is regulated by bending the same around the grooved rod N', the guiding of the conductor to such rod being regulated by the pin n, through which the conductor passes from the spool. When only one spool 65 is used, the friction of the spring thereon

must be greater than when a plurality of spools are used. It is also necessary to increase the tension by bending the conductor around the rod N' more times when only a single spool is used. 70

The pressure with which the pulleys V' V² engage the coiled cord may be regulated by adjusting the screws U⁴, thereby regulating the tension of the springs U³, which force the journals of the shaft u² toward the shaft U. 75 The coiled cord is retained in contact with the periphery of the pulley V' by means of the guiding-springs W', the tension of which may be regulated by the screw w'. 80

The speed of rotation of the pulleys V' V² must be varied according to the number of conductors used in making the cord. The speed with which the cord is formed is greater when the cord is composed of more than one conductor. Consequently the pulley must rotate at slow speed when a single conductor is used and at a gradually-increased speed when two, three, or four conductors are employed. The speed of rotation of the pulleys is varied by varying the 85 relative sizes of the meshed gear-wheels T² and t². 90

From the foregoing description it will be observed that I have invented an improved machine for winding a flexible wire into 95 spiral form, and more particularly a machine for making switchboard-cords which is simple in construction and operation, but the operation of which results in the cord being quickly made of one or more conductors. 100

Having now fully described my invention, what I claim as new, and desire to secure by Letters Patent, is—

1. In a machine of the character described, the combination with a mandrel, of a carrier, 105 a post for supporting said mandrel extending concentrically through said carrier, means for supporting a spool of wire on said carrier eccentrically to the axis of said mandrel, and means for relatively rotating said carrier and 110 mandrel.

2. In a machine of the character described, the combination with a mandrel, of a carrier, means for supporting a plurality of spools of wire on said carrier, a separate guide mounted upon the carrier for directing the wire from each spool to the mandrel, said guides terminating at different heights, and means for relatively rotating said carrier and mandrel. 115 120

3. In a machine of the character described, the combination with a mandrel, of a carrier, means for supporting a plurality of spools of wire upon said carrier, a plurality of guides for directing the wire from the spools to the 125 mandrel, means for adjustably supporting said guides upon said carrier, and means for relatively rotating said carrier and mandrel.

4. In a machine of the character described, the combination with a mandrel, of a carrier, 130

means for supporting a spool of wire on said carrier, means for relatively rotating said carrier and mandrel, and means located on the opposite side of the mandrel from the carrier 5 for drawing the coiled wire from the mandrel.

5. In a machine of the character described, the combination with a mandrel, of a carrier, means for supporting a spool of wire on said carrier, means for relatively rotating said carrier and mandrel, a pair of oppositely-rotated pulleys between which the coiled wire passes from the mandrel, and means for rotating said pulleys.

6. In a machine of the character described, 15 the combination with a mandrel, of a carrier, means for supporting a spool of wire on said carrier, means for relatively rotating said carrier and mandrel, a pair of oppositely-rotated pulleys between which the coiled wire passes 20 from the mandrel, means for rotating said pulleys, and means for forcing the coiled wire against one of said pulleys.

7. In a machine of the character described, the combination with a mandrel, of a carrier, 25 a post for supporting said mandrel extending concentrically through the carrier, means for rotatively supporting a spool of wire on said carrier eccentrically to the axis of said mandrel, means for regulating the rotation of said 30 spool, and means for relatively rotating said carrier and mandrel.

8. In a machine of the character described, the combination with a mandrel, of a carrier, means for supporting a spool of wire on said carrier, means on said carrier interposed between said spool and mandrel for retarding 35 the movement of the wire, a guide for directing the wire to said retarding means, and means for relatively rotating said carrier and mandrel.

40 9. In a machine of the character described, the combination with a mandrel, of a carrier, means for rotatively supporting a spool of wire on said carrier, means for regulating the

rotation of said spool, means interposed between said spool and mandrel for retarding the movement of the wire, a guide for directing the wire to said retarding means, and means for relatively rotating said carrier and mandrel.

50 10. In a machine for making switchboard-cords, the combination with the mandrel, of a carrier, mean upon said carrier for supporting a conductor to form the cord, a shaft, means for rotating said shaft, gearing interposed between said shaft and carrier for rotating the latter, and means actuated by said shaft for drawing the coiled cord from the mandrel.

60 11. In a machine for making switchboard-cords, the combination with a mandrel, of a carrier, means upon said carrier for supporting a conductor to form the cord, a shaft, means for rotating said shaft, gearing interposed between said shaft and carrier for rotating the latter, and guide-pulleys between 65 which the coiled cord passes from the mandrel.

70 12. In a machine for making switchboard-cords, the combination with a mandrel, of a carrier, means for rotatively supporting a plurality of spools containing conductors upon said carrier, means for regulating the rotation of said spools, guides mounted on said carrier through which the conductors pass to 75 the mandrel, means for adjusting said guides, means interposed between said spools and mandrel for retarding the movement of the conductors, means for drawing the coiled cord from the mandrel, and means for relatively 80 rotating said carrier and mandrel.

In testimony whereof I sign this specification in the presence of two witnesses.
